Inventor

Theodore Wallis

UNITED STATES PATENT OFFICE.

THEODORE WALLIS, OF SCIPIO, NEW YORK.

IMPROVEMENT IN SHEARS.

Specification forming part of Letters Patent No. 43,809, dated August 9, 1864.

To all whom it may concern:

Be it known that I, THEODORE WALLIS, of the town of Scipio, in Cayuga county and State of New York, have invented a new and useful Improvement in Hand-Shears or Nippers; and I do hereby declare that the following is a full, clear, and exact description of the same, reference being had to the accompanying drawing, and to the letters of reference marked thereon.

The nature of my invention consists in employing a pulley and its connections (to be hereinafter described) between the two levers in machines where compound levers are used for the purpose of largely reducing the friction of the joint.

A side view of the nippers is represented in the drawing with all the parts in their relative position. A is the lower or single side of said shears. B and C are the two levers on the opposite side. At D in A and E in B will be seen the cutting-edges. The shears have connections like those represented at F, G, and H on both sides of the levers A

and C. The levers C and A are connected by the piece F, and the levers B and C are joined by the two connections G and H through the center of pulley I. It will be noticed that one side of the pulley I rests in a curve in the end of the lever B, whose radius equals the radius of the pulley I. It will be obvious that this arrangement will greatly lessen the force required to operate the cutting-edges of the shears, as will be seen when the ends of the levers A and C are made to approach and recede from each other.

Having thus described the construction and operation of my invention, what I claim as new, and desire to secure by Letters Patent, is—

The pulley I and the connections G and H, in combination with levers C and B, as set forth.

THEODORE WALLIS.
